UNITED STATES PATENT OFFICE.

FLORENZ KEISER, OF POTTSTOWN, PENNSYLVANIA, ASSIGNOR OF ONE-HALF TO GEORGE J. FELKER, OF SAME PLACE.

CAR-AXLE BOX.

SPECIFICATION forming part of Letters Patent No. 257,720, dated May 9, 1882.

Application filed August 19, 1881. (No model.)

To all whom it may concern:

Be it known that I, FLORENZ KEISER, a citizen of the United States, residing at Pottstown, Montgomery county, Pennsylvania, have invented certain Improvements in Axle-Boxes, 5 of which the following is a specification.

My invention relates to an improvement in that class of axle-boxes in which the lid swings laterally across the face of the box, the object 10 of my invention being to so construct and hang a lid that it can be readily opened, will be self-retaining in its opened position, will close automatically when a shaking or jarring movement is imparted to the box, and when closed 15 will effectually prevent the entrance of dust to the interior of the box.

In the accompanying drawings, Figure 1 is a perspective view of my improved axle-box with the lid closed; Fig. 2, the same with the lid 20 opened; Fig. 3, a longitudinal section of the box on a larger scale; and Figs. 4 and 5, front views of the box, showing the method of hanging the lid and retaining the same when elevated.

25 A is the casing of the box, having in front the usual opening, *a*, through which access is had to the interior, this opening being closed by a lid, B, pivoted to the upper corner of the box and adapted to swing laterally across the 30 face of the same, the pivot-bolt passing through a lug, *b*, on the box, and having in the rear of said lug a nut, preferably adapted to a recess in the top of the box, so as to prevent it from turning. The lower edge of the lid B is beveled, 35 and is adapted to a beveled projection, *d*, on the box, as shown in Fig. 3, so as to form a tight joint, and on the upper edge of the lid is a recessed projection, *e*, which, when the said lid is depressed, receives the rib *f* on the upper 40 front edge of the box A, thereby holding the lid firmly against the front of the box and preventing the entrance of dust or dirt to the interior of the same. The end *x* of the projection *e* serves, by contact with the lug *b*, to limit

the movement of the lid B in the direction of 45 the arrow, Fig. 5, and this stop is so arranged that when the lid is fully opened there will be a slight preponderance of weight on one side, *w*, of a dotted line, *y*, drawn vertically through the center of the pivot-bolt, so that the tendency of the lid when opened will be to remain open. The preponderance of weight on the side *w* of the line *y* is very slight, however, and when the car begins to move a little shaking of the lid is sufficient to so jerk the lid that 50 the preponderance will be on the opposite side, *w'*, of the line *y*, in which case the lid will instantly fall, its weight in falling causing the lid to be wedged in its beveled seat.

Instead of forming a beveled projection, *d*, 60 on the box A, as shown, an L-shaped projection may be made thereon for the reception of a rib on the edge of the lid.

I am aware that an axle-box lid has been hinged to the box at one side of the opening *a*; 65 but in this case the width of the opening is contracted, the casing of the box at the side of the opening *a* being necessarily wider than in my improved box in order to provide a hinge-lug of proper strength.

70 I claim as my invention—

1. The combination of the box A and lug *b* on the top of the same, near one side, with the lid B, hung at one of its upper corners to the said lug *b*, and having a stop, *x*, for limiting 75 its movement and maintaining it in a balanced position when opened, as set forth.

2. The combination of the box A, having a rib, *f*, on its upper front edge, with the laterally-swinging lid B, having on its upper edge a 80 recessed projection, *e*, as set forth.

In testimony whereof I have signed my name to this specification in the presence of two subscribing witnesses.

FLORENZ KEISER.
